WINDOW OPERATOR

Edmund Peremi and Louis Toth, Manhasset, N. Y.

Application July 4, 1939, Serial No. 282,783

6 Claims. (Cl. 268—117)

This invention relates to window operators for casement windows or the like.

It is among the objects of this invention to provide a casement window operator by which the window may be swung between its open and closed positions without manually pushing or pulling the window, and further, which holds the window in any desired position between or at its limits of movement without resorting to supplementary holding devices. It is another object of this invention to provide an operator of the above nature which takes up a minimum amount of room in the window opening, and yet which is sufficiently extendable to completely open the window.

Other objects will be in part apparent and in part pointed out hereinafter.

The invention accordingly consists in the features of construction, combinations of elements, and arrangements of parts, as will be exemplified in the structure to be hereinafter described, and the scope of the application of which will be indicated in the following claims.

In the drawings, in which are shown several embodiments of my invention:

Figure 1 is a top plan view of the operator attached to a projected casement window;

Figure 2 is an enlarged fragmentary sectional elevation taken along the line 2—2 of Figure 1;

Figure 3 is a perspective view of a modified form of operator;

Figure 4 is an enlarged fragmentary inverted view of the operator, portions thereof being broken away, and other portions being shown in section;

Figure 5 is a fragmentary bottom plan view of the operator, portions thereof being broken away, and other portions being shown in section;

Figure 6 is a fragmentary perspective view of another modification of our operator;

Figure 7 is a fragmentary top plan view of the operator shown in Figure 6;

Figure 8 is a fragmentary side elevation of the operator shown in Figure 6, portions being broken away and portions being shown in section;

Figure 9 is a top plan view, partly in section, of another form of our operator;

Figure 10 is a sectional elevation taken along the line 10—10 of Figure 9;

Figure 11 is a sectional elevation taken along the line 11—11 of Figure 9; and,

Figure 12 is a sectional elevation taken along the line 12—12 of Figure 9.

Similar reference characters refer to similar

parts throughout the various views of the drawings.

Referring first to Figure 1 of the drawings, a base plate 15, which is adapted to be secured to the sill of the window opening has mounted thereon a bottom bar 16 of the window frame, and these two parts have secured thereto one element 17 of a hinge generally indicated at 18. Hinge 18 as shown is of the type described in detail in our United States Letters Patent No. 1,955,653, and further is of the type provided for a projected casement window. Hinge 18 accordingly includes a movable element 19 to which is secured the bottom sash bar 20 of the window sash. 10 Also secured to base plate 15 is an operator generally indicated at 21, which includes relatively extensible members generally indicated at 22, which are attached to sash bar 20. Operator 21 also includes a manually rotatable crank or the like 23 which upon operation swings the window sash.

Operator 21 comprises a base 24 secured by screws 25 to base plate 15. A web 26 (Figure 2) extends upwardly from base 24 and is joined to another web 27 also extending upwardly from base 24. These two webs support a journal or housing 28 whose axis extends diagonally with respect to web 27 and base 24 of the operator.

Housing 28 rotatably carries a shaft or the like (not shown) to one end of which is attached crank 23 (Figure 1) and to the other end of which is attached one element or fork of a universal joint, the other element 30 of which is secured to the inner end of the relatively extensible members 22.

Members 22 include a tubular interiorly threaded member 31 which threadably receives a screw 32 the outer or exposed end of which is pivoted at 33 to a lug 34 or the like secured to sash bar 20. It will now appear that upon operation of crank 23, tubular element 31 will be rotated by reason of its connection to the crank through the universal joint elements 29 and 30, and in accordance with the direction of rotation of element 31, screw 32 is extended or projected from the tube or is drawn thereinto, as the screw is constrained against rotation by reason of its attachment to lug 34. Thus, the only possible movement of screw 32 with respect to tube 31 is axial, although both elements are pivotable with respect to operator 21 and accordingly base plate 15.

Assuming that element 31 rotates in the direction to draw screw 32 into element 31, sash bar 20 is swung clockwise until it reaches the dotted line position shown in Figure 1. Reverse rotation

of element 31 results in the extension of screw 32 and the consequent opening movement of sash bar 20.

By reason of the threaded relation of elements 31 and 32, supplementary sash locking devices are unnecessary as the sash is effectively locked in any desired position and furthermore rattling of the sash in its opened, closed, or in any intermediate position is precluded as there is little or no play in the window operating elements 21 and 22 or in the hinge 18. Also, by reason of the telescoping relationship of elements 31 and 32, these elements occupy but a limited amount of space in the window opening, and aside from their efficiency in operation, are both sturdy and neat in appearance.

Referring now to the modified form of operator generally indicated at 35 in Figure 3, a base 36 carries a substantially crescent-shaped or U-shaped support 37 to which is secured in any suitable manner a curved wall portion 38 (Figure 5) on the top of which is mounted a cover plate 39. A web 40 (Figure 3) is secured to support 37, wall 38 and top 39, and through this web and top extends a journal 41 or the like (Figures 3 and 4) whose axis is diagonal to the plane of the web and to the plane of bottom or base 36. As shown in Figure 5, journal 41 opens into the enclosure between top 39 and base 36 (Figure 3) and rotatably carries a split shaft generally indicated at 42 in Figure 4. Shaft 42 comprises a pair of elements 43 and 44 joined by a key 45 or the like. Shaft element 43 includes a reduced portion 46 which extends into the shank of a crank 60, by which the operator is manually operated. Shaft element 44 has connected thereto one end 47a of a flexible cable 47 which extends into the enclosure between base 36 and top 39 of the operator.

Base 36 (Figure 4) has a circular groove 48 and top 39 has a similar registering groove 49, in which a cylindrical housing 50 is rotatably mounted. That portion of housing 50 (Figure 5) which is exposed, i. e. which lies outside of curved wall 38, is formed with a tubular projection 51 adapted to journal a rotatable stud 52 having a central core 53 in which the other end 47b of flexible cable 47 is secured as by a pin 54. The inner end of stud 52 has a shoulder 55 which abuts the inner end of projection 51 to prevent displacement of stud 52 to the right as viewed in Figure 5. The outer end of the stud has a reduced threaded end 56 about which a nut 57 is threaded against the outer end of projection 51; nut 57 and shoulder 55 preclude axial displacement of stud 52 with respect to projection 51. Threaded end 56 of stud 52 has threaded therein the inner end of an elongated tubular element 58 similar to element 31 shown in Figure 1. This element 58 is interiorly threaded and threadably receives a screw 59 similar to screw 32 shown in Figure 1. The outer end of screw 59 (Figure 3) is adapted to be secured to the window sash as described with respect to screw 32 (Figure 1) to effect opening and closing of the sash upon actuation of the operator.

Operator 35 (Figure 3) is adapted to be secured to a base plate such as base plate 15 (Figure 1) so that upon rotation of crank 60 (Figure 4) flexible cable 47 turns to rotate element 58. As element 58 rotates, screw 59 (Figure 3) is extended from or drawn into element 58 to swing the window. As the window swings, however, elements 58 and 59 also swing, and accordingly cylindrical housing 50 rotates in its grooves 48

and 49 (Figure 4). This rotation is possible by reason of the flexible nature of cable 47 which assumes various positions within housing 50 (Figure 5) as the housing follows the swinging movement of element 58 and screw 59.

Generally indicated at 61 in Figure 6 is another modification of our operator. This form includes a base 62 and a top 63, which with a pair of wall portions 64 and 65 (Figure 7) form an enclosure 66 (Figure 8) in which a cup-shaped housing 67 is rotatably disposed. Preferably walls 64 and 65 are integral with top 63 and are connected to bottom 62 as by screws 68 or the like (Figure 8) which extend through bottom 62 into walls 64 and 65. Top 63 has a recess 69 formed therein, and from this recess a boss 70 extends angularly and upwardly from enclosure 66. Boss 70 journals a stud 71, the outer end of which is connected to the shank of a crank 72 as by a set screw 73. The inner end of stud 71 extends into enclosure 66 and carries a coaxial bevel gear 74 which is adapted to rotate within the enclosure and within recess 69 upon rotation of crank 72.

The lower end of a stud 75 is disposed in bottom 62 and the stud extends upwardly into enclosure 66 through the bottom of cup-shaped housing 67. Bevel gear 76 is mounted to rotate in enclosure 66 about stud 75 and is in mesh with gear 74. Housing 67 has an opening 77, the edges of which fit into a groove 78 formed on the inner end of a tubular threaded element 79 similar to element 31 (Figure 1). The inner end of element 79 (Figure 8) carries a small bevel 80 which meshes with bevel 76 and accordingly is rotated thereby. An arm 81 extends through bevel 80 and is rotatably connected to element 79, its other end lying within enclosure 66 and being pivotally mounted on the upper end of stud 75 between a pair of washers 82 and 83. Washers 82 and 83 and the inner end of arm 81 are held in assembled relation on the upper end of stud 75 by a screw 84 threaded into the stud.

Threaded tube 79 (Figure 6) is adapted to threadably receive a screw (not shown) similar to screw 32 (Figure 1). Upon actuation of operator 61 (Figure 6) tube 79 and its screw operate the window as hereinbefore described with respect to tube and screw 31 and 32 respectively (Figure 1). In operation of operator 61 (Figure 8) rotation of bevel 74 by crank 72 drives bevel 76 which in turn operates bevel 80. This causes element 79 not only to rotate, but also to pivot about the axis of stud 75, as the window swings in one direction or another. As element 79 pivots about stud 75, housing 67 turns within enclosure 66. It will now appear that the bevels in enclosure 66 comprise a differential which not only rotates element 79, but also permits swinging of this element as the window operates between the full and dotted line positions shown in Figure 6. As described above with respect to operator 21 (Figure 1) operator 61 (Figure 6) is also adapted to be secured to a suitable base plate such as plate 15 (Figure 1).

Turning now to Figures 9, 10 and 11, wherein still another form of our operator is shown, a housing 85 (Figures 9 and 11) is suitably secured as by brackets 86 to a base 87, in turn secured to base plate 15. Housing 85 and base 87 form an enclosure 88 in one corner of which (as shown in Figures 9 and 10) is rotatably disposed a bracket generally indicated at 89. Bracket 89 includes an upper portion 90 which projects through the top 70 of housing 85 (Figure 10) and is hollow to receive

the upper end of a stud or shaft 91 to the upper end of which is connected a crank 92. The lower end of shaft 91 is rotatably mounted in base 87 and is rotatable with respect both to the base and to bracket 89. Upper portion 90 of bracket 89 receives a bevel gear 93 which is carried by and secured to shaft 91 by a pin 94 or the like.

Bracket 89 also includes a portion 95 angularly disposed with respect to bracket portion 90 and this bracket portion 95 rotatably supports one end 96a of a screw 96 disposed within enclosure 88. End 96a of the screw which lies within bracket 89 carries a bevel 97 which meshes with bevel 93 so that rotation of bevel 93 imparts rotation not only to bevel 97 but also to screw 96. As noted above, bracket 89 is rotatable within enclosure 88 and thus will turn about the axis of shaft 91. Similarly, screw 96 will swing about the same axis.

An interiorly threaded nut 98 is threaded on screw 96 and, as shown in Figure 11, is constrained against rotation about the screw by reason of its disposal between the bifurcations 99a and 99b of a bifurcated lever 99. Nut 98 is also pivotally related to bifurcations 99a and 99b by oppositely extending studs 100 and 101 which extend respectively into suitable holes formed in bifurcations 99a and 99b. From the above, accordingly, it appears that rotation of screw 96 effects axial movement of nut 98 with respect to the screw.

Lever 99 (Figures 9 and 11) is fulcrumed by a pin 102, which extends through the lever and through a block 103 secured to plate 89 in which it is maintained against axial displacement in any suitable manner. A friction slide shoe 105 (Figure 12) is secured to the outer end of lever 99, and slides back and forth in a track 106 secured to sash bar 20 as the window swings. Thus, movement of lever 99 operates the window.

Upon rotation of crank 92 (Figure 10) the meshing bevels 93 and 97 rotate screw 96, causing movement axially thereof of nut 98. Assuming such rotation of screw 96 as will move nut 98 downwardly, as viewed in Figure 9, this movement of the nut moves lever 99 clockwise, i. e. in a direction to close the window. However, as the nut moves toward the free end of screw 96, screw 96 is swung toward the lever fulcrum 102 until the screw and lever reach their dotted line positions wherein the window is completely closed. Reverse rotation of the various operating parts, of course, results in opening movement of the window. Furthermore, by reason of the relationship between nut 98 and screw 96, the window is securely held not only in its open and closed positions, but also in any intermediate position, as forces exerted on the window normal to its plane are ineffective to cause rotation of screw 96.

Accordingly, it will be seen that we have provided a casement window operator characterized by simplicity in design and efficiency in operation, in addition to its ruggedness and neat appearance. Thus, the various objects hereinabove set forth are practicably attained.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. An operator for a casement window or the like pivotally disposed in a frame comprising,

in combination, a housing secured to said frame, said housing including a substantially horizontal base portion and a substantially vertical web portion lying in a plane parallel to the plane of said frame, a tubular journal member secured to and extending through said web portion, the axis of said member extending diagonally of said web and base portions, a driving member rotatably mounted in said journal member, a hand crank on the outer end of said driving member and located to one side of the window opening, a threaded element, means operatively connecting said element to said member so as to rotate upon rotation of said crank, a second threaded element threadably associated with said first threaded element and constrained against rotation with respect thereto, whereby upon rotation of said first element by said crank said second element is moved axially of the first, and means for connecting said second element to the window for operation thereof.

2. An operator for a casement window or the like pivotally disposed in a frame comprising, in combination, a housing secured to said frame adjacent that corner thereof at which one corner of the window is pivoted, said housing including a base portion adapted to be secured to said frame and extending inwardly thereof, said housing also including a web portion integral with and extending upwardly from said base portion between the inner and outer edges thereof, a tubular journal member secured to and extending diagonally through said web portion, a driving member rotatably mounted in said journal member, a hand crank on the outer end of said driving member and located to one side of the window opening inwardly and upwardly of said web portion, a threaded element, means operatively connecting said element to said member so as to rotate upon rotation of said crank, a second threaded element threadably associated with said first threaded element and constrained against rotation with respect thereto, whereby upon rotation of said first element by said crank said second element is moved axially of the first, and means for connecting said second element to the window for operation thereof.

3. An operator for a casement window or the like pivotally disposed in a frame comprising, in combination, a housing secured to said frame, said housing including a substantially horizontal base portion and a substantially vertical web portion extending upwardly from said base portion, a tubular journal member secured to and extending through said web portion, a drive shaft rotatably mounted in said journal member, a hand crank on the outer end of said driving member and located adjacent one side of the window opening, a threaded element, universal joint means for connecting said threaded element to said drive shaft to effect rotation of said element upon operation of said crank, a second threaded element threadably associated with said first threaded element and constrained against rotation with respect thereto whereby upon rotation of said first element by said crank said second element is moved axially of the first, and means for connecting said second element to the window for operation thereof.

4. An operator for a casement window or the like pivotally disposed in a frame comprising, in combination, a housing secured to said frame, said housing including a substantially horizontal base portion adapted to be secured to said frame and a substantially vertical web portion ex-

tending upwardly from said base portion, a tubular journal member secured to and extending through said web portion, a drive shaft rotatably mounted in said journal member, a hand crank on the outer end of said drive shaft and located at one side of the window opening, an interiorly threaded elongated tubular means operatively connected to said member so as to rotate upon rotation of said crank, an exteriorly threaded elongated element threadably associated with said tube and constrained against rotation with respect thereto whereby upon rotation of said tube by said crank said element is moved axially of said tube so as to telescope therewithin when the window is closed, and means for connecting 15 said element to the window for operation thereof.

5. An operator for a casement window or the like pivotally disposed in a frame comprising, in combination, a housing including a horizontal base portion and a vertically extending web portion, said base portion being adapted to be secured to said frame adjacent one side of the window opening, a tubular journal member secured to and extending through said web portion, a drive shaft rotatably mounted in said journal member, a hand crank secured to the outer end of said drive shaft and located adjacent one side of the window opening, a threaded element, flexible means operatively connecting said element to said shaft whereby said element may be rotated upon operation of said 30

crank, a second threaded element rotatably associated with said first threaded element and constrained against rotation with respect thereto whereby upon rotation of said first element by said crank said second element is moved axially of the first, and means for connecting said second element to the window for operation thereof.

6. An operator for a casement window or the like pivotally disposed in a frame comprising, in combination, a housing including a horizontal base portion and a vertically extending web portion, said base portion being adapted to be secured to said frame adjacent one side of the window opening, a tubular journal member secured to and extending through said web portion, a drive shaft rotatably mounted in said journal member, a hand crank secured to the outer end of said drive shaft and located adjacent one side of the window opening, a threaded element, gear means forming a universal connection between said element and said shaft whereby said element is rotated upon rotation of said crank, a second threaded element threadably associated with said first threaded element and constrained against rotation with respect thereto whereby upon rotation of said first element by said crank said second element is moved axially of the first, and means for connecting said second element to the window for operation thereof.

EDMUND PEREMI.
LOUIS TOTH.
